CONTINUOUS LOOP TAPE RECORDER OR SIMILAR ARTICLE

James B. Stewart, North Brunswick, N.J., assignor to
Westinghouse Electric Corporation, East Pittsburgh,
Pa., a corporation of Pennsylvania

Filed Sept. 30, 1964, Ser. No. 81,945

Term of patent 14 years

(Cl. D26—14)

FIG.2.

FIG.3.

FIG.1.

FIGURE 1 is a front view of a continuous loop tape recorder embodying my new design;

FIG. 2 is a top view embodying my new design; and

FIG. 3 is a side view embodying my new design.

The sides not shown in the above figures are similar in appearance to the respective sides therein shown.

The dominant features of my design reside in the portions shown in full lines.

The holes in the fenestrated cover indicated by dots are continuous over the top and down the sides within the boundaries shown. A portion of the drawing figures is diagonally lined to indicate translucency.

I claim:

The ornamental design for a continuous loop tape recorder or similar article, substantially as shown and described.
